UNITED STATES PATENT OFFICE.

VALERIAN ALEXEEFF, OF ENSELI, PERSIA.

AUTOMATIC TELEPHONE SYSTEM.

991,260.

Specification of Letters Patent.

Patented May 2, 1911.

Application filed June 19, 1908. Serial No. 439,331.

To all whom it may concern:

Be it known that I, VALERIAN ALEXEEFF, a subject of the Russian Emperor, residing at Enseli, Persia, have invented a certain 5 new and useful Automatic Telephone System, of which the following is a specification.

The invention relates to automatic telephone systems which allow each subscriber 10 to directly obtain connection with another subscriber, without calling up an exchange office for making this connection, and consists in a construction which enables the connection to be obtained quickly and without the 15 necessity of employing a complex system of conductors while, at the same time, other persons are prevented from hearing the conversation. The number of subscribers may without inconvenience amount to approximately 20 four hundred. The whole system is arranged in such a manner, that in the case of only a small number of subscribers there is provided a selecting-switch station, to which the telephone of each subscriber is 25 joined. In the case of a greater number of subscribers, the telephones of the subscribers form groups, each of which has selecting-switch substation and the connection of subscribers of different groups takes 30 place over a central selecting-switch station, to which are joined the selecting-switch sub-stations of all groups. The new system is peculiarly suitable for private establishments, small towns and villages.

35 In the drawings are shown arrangements for 10 and 100 subscribers.

Figures 1 and 2 are vertical and horizontal sections respectively through the automatic central selecting-switch station as used 40 in the case of a greater number of subscribers for connecting the selecting-switch sub-stations of different groups. Fig. 3 shows part of the internal mechanism. Figs. 4 and 5 illustrate on a larger scale the co-action 45 of the automatically adjustable contact plates of the central selecting-switch station. Fig. 6 is a horizontal section of the slide-contact cylinder. Fig. 7 is a semi-diagrammatic plan view partly in section illustrating the 50 working of the pawl upon the rotary disk, and Fig. 8 is a vertical section of part of this mechanism. Fig. 9 is a vertical central section of the selecting-switch station of each 55 group of subscribers. Figs. 10 and 10^a show the sliding-contacts of the selecting switch station of Fig. 9 on a larger scale. Figs. 11

and 12 are vertical sections of the particular circuit closing mechanism belonging to a subscriber's instrument. Fig. 13 shows the reversing key, with contacts and connections. 60 Fig. 14 is a vertical section of an optical indicator associated with the circuit closing mechanism. Figs. 15, 16 and 17 illustrate the connections when the calling telephone (Fig. 15) is to be connected to the called telephone (Fig. 17) through one single selecting-switch station (Fig. 16). Figs. 18 to 22 illustrate the connections when the calling telephone (Fig. 22) through its selecting-switch (Fig. 21) is connected by means of 70 the central selecting-switch (Fig. 20) with the selecting-switch (Fig. 19) of the subscriber to be called (Fig. 18) and through this latter switch with the corresponding telephone. Fig. 23 is a diagrammatic view 75 illustrating the connections between several stations of the system.

In the central selecting switch (Figs. 1 and 2) in the annular wall of the casing M and in two superposed rings D and E there 80 are bearings for two superposed groups of radial rods C¹ C² C³ . . . C¹⁰. To the rods C are fixed electro-magnets B¹ B² B³ . . . B¹⁰ and small contact-disks e¹. The coils of the electro-magnets B are excited by current 85 from a local battery VII (Fig. 20), as will be explained hereinafter. Electro-magnets A¹ A² A³ . . . A¹⁰ are supported in the casing M in radial line with the magnets B¹ . . . B¹⁰ respectively, but the rods C¹ . . . C¹⁰ 90 pass through the cores of the electro-magnets A without making contact therewith. The electro-magnets A can be excited by current from the line wires (Fig. 20). The casing M and ring D are of electrically non-conductive material; the ring E is conductive, but is insulated from the rods C¹ . . . C¹⁰ by non-conductive sleeves e. Two superposed pairs of electro-magnets A and B belong to 95 the same subscriber. Springs e on the rods 100 C¹ . . . C¹⁰ tend to thrust the latter toward the center of the casing M and move the cores of the magnets B¹ . . . B¹⁰ away from the cores of the magnets A¹ . . . A¹⁰. The two magnetic forces and the force of the 105 springs are so proportioned, that any two of them acting collectively overcome the third force. In the position of rest shown in Fig. 1, with no connections made for the transmission of telephonic messages, the 110 magnets A and B are in contact with each other, for reasons which will be explained

- hereinafter. Separation of the respective electro-magnet B from electro-magnet A takes place only when the corresponding magnet A is excited by current from the line.
- 5 If one of the lower electro-magnets B (Fig. 1) is repulsed from its electro-magnet A, when the latter receives current impulses from the calling-telephone, it brings the contact-disk c^1 into contact with the ring E.
- 10 The contact ring c^1 on the upper rods $C^1 \dots C^{10}$ remains, when displaced by the magnet B, in contact with the respective contact-piece $d^1 \dots d^{10}$ of the ring D. At the outer end of each of the lower rods $C^1 \dots C^{10}$ there is a knob or button c^5 with a recess c^8 therein, and near the said knob or button there is a slidable disk c^3 normally thrust against a fixed disk c^2 by a spring c^4 .
- Between the upper and lower magnets B (Figs. 1, 4 and 5) there are two slide-contacts b and b^1 . The slide b consists of three metal plates b^2 b^3 and b^4 of different widths. The plates b^2 and b^4 are connected to a positive wire, and the plate b^3 is connected to the negative wire of the local battery VII. (Fig. 20). The slide b^1 consists of two contact-plates b^5 and b^6 , to which the coil of the lower magnet B is connected. No connection can be made to the said coil other than through the contact-plates b^5 and b^6 . It will be seen from Figs. 4, 5 and 20 that by displacement of the magnets and slides relatively to each other the direction of the current in the lower magnet is reversed, the flow being either from b^2 to b^5 and from b^3 to b^6 , or from b^2 to b^5 and from b^4 to b^6 , the contacts b^2 and b^4 being electrically of the same sign. The slide-contacts are of such a size, that the lower electro-magnet B never becomes free from circuit, whether the upper electro-magnet B is displaced against the lower electro-magnet B, or contrary. The upper electro-magnets B, are connected to the local battery VII, from which they receive their current. Around about the casing M there are arranged outwardly respectively above and below the lower group of rods $C^1 \dots C^{10}$, two contact-rings c^6 and c^7 with which the disks c^3 make contact when the rods $C^1 \dots C^{10}$ are moved inward.
- The upper and lower rods $C^1 \dots C^{10}$ are connected in pairs by non-conductive links g and metallic bell-crank levers $G^1 \dots G^{20}$ to a slide-rod $F^1 \dots F^{20}$ (Figs. 1 and 3); the levers G and rods F are marked, in the drawing, with indices corresponding to the indices of the respective rods C. In the normal position of rest, shown in Fig. 1, the inner ends of the levers G connected to the lower rods C abut against the flange e^1 of an annular contact E^1 within the ring E, but when the magnets A and B are thrust apart, the levers G go down and their contact with the part E^1 is broken. The contact E^1 is connected with the earth and insulated from the ring E. Each of the rods $F^1 \dots F^{20}$ consists of an upper metal part f and a lower non-conductive part f^1 , and the said rods are movable in guides $h^1 \dots h^{20}$ within an axially movable non-conductive cylinder H. The guides $h^1 \dots h^{20}$ are fixed to the cylinder H and their lower ends slide within a fixed, non-conductive cylinder J; the latter also contains movable plates $i^1 \dots i^{20}$ which are supported by springs i^0 , and against which the rods $F^1 \dots F^{20}$ can abut. The movable cylinder H has a double bottom J^3 , to which is fixed the armature J^4 of an electro-magnet J^2 , so that the cylinder H can be moved by means of the magnet J^2 . A spring J^1 tends to retain or to bring back the cylinder H in the normal position in which the said cylinder is shown in Fig. 1. The non-insulated part of each rod $F^1 \dots F^{20}$ is normally (Figs. 1 and 3) only to a very small extent in contact with the respective guides $h^1 \dots h^{20}$, so that a very small movement of the cylinder H relatively to the rod F is sufficient to produce a change of connections. To the guides $h^1 \dots h^{20}$ are connected wires $k^1 \dots k^{20}$ leading to terminal-screws $K^1 \dots K^{20}$ at the wall of the casing M.
- In obtaining connection between two telephones, for the purpose of conversation, first the slide-rod F belonging to the calling telephone is moved downward, and then that belonging to the telephone of the subscriber called up. The other slide-rods remain at rest. For this purpose an arm M^1 carrying an electro-magnet N is rotatably mounted on the casing M and provided with fingers m m^1 adapted to engage behind the disks c^3 , so that these fingers prevent the displacement of these lower rods C F opposite which the magnet N is placed. A brush n^3 to which the coil of the magnet N is connected rubs on the contact ring c^6 fixed to the casing M (Fig. 1). The magnet N is traversed by a movable iron rod n^1 with a disk n fixed thereto, and a spring n^2 tends to thrust this rod outward. The coil of the magnet N is also connected to a contact-ring n^5 rubbing against a brush n^4 which is connected to the coil of the magnet J^2 . Excitation of the magnet N causes the disk n to be attracted so that the inner end of the rod n^1 is thrust into the recess c^8 in the knob c^5 with which the rod n^1 is in line, so that the arm M^1 is locked in line radially with the respective rod $C^1 \dots C^{10}$. The rod n^1 thrusts the respective lower magnet B inward until the disk c^1 on the rod C comes into contact with the ring E. From the magnet N the circuit is led through the brush n^3 to the contact ring c^6 . The contact ring n^5 receives circuit through brush n^4 from the magnet J^2 , whose one coil-end is connected with brush n^4 while the other coil-

end is fixed to battery I. The other pole of battery I is connected with the ring c^7 , which can be electrically connected to the ring c^6 by the disk c^3 (Figs. 1 and 20).

- 5 Rotation of the arm M^1 in one direction (Figs. 1, 7 and 8) is produced by means of an electro-magnetic device, and in the other direction by a weight P^1 attached to a cord P, which is fastened to the hub or boss of 10 the arm M^1 and passes over a roller P^2 . The electro-magnetic-device referred to comprises a pawl o^2 connected to the sliding-core o of an electro-magnet O and adapted to engage the toothed upper surface of a ring or 15 flange M^2 fixed to the boss of the arm M^1 . The electro-magnet O, which can be excited by current from the line wire, is rotatable about a vertical pivot o^9 and can be automatically rotated to and from the ring M^2 20 by two solenoids o^4 and o^5 , a spring o^6 and battery III. The armature of the magnet O, consisting of a rod o with a disk o^1 fixed thereto, is acted on by a spring o^{11} . Fixed to the magnet O is arm o^9 bifurcated 25 at its free end to engage a pin o^{12} fixed to the armature o^3 of the solenoid o^4 . The solenoid o^4 is fixed to the casing M, and the solenoid o^5 is fixed to an iron rod o^7 which projects from the armature o^3 and passes 30 through the solenoid o^4 . The spring o^6 tends to thrust the solenoid o^5 away from the casing M, but the solenoids o^4 and o^5 , acting together, are able to overcome the force of the spring o^6 . The coil of the magnet o^5 is connected to the battery II (Fig. 35 20). To the U-shaped armature o^3 is pivoted a pawl o^8 , which enters simultaneously with the pawl o^2 in the toothed ring M^2 as long, as magnet o^5 is pushed outward by 40 the spring o^6 and prevents the returning of arm M^1 by the weight P^1 while the pawl o^2 engages the next tooth of ring M^2 . The solenoid o^4 is in a circuit connected to the battery III. This circuit can be opened and 45 closed by means of a cam m^3 on the ring M^2 (Fig. 7) and resilient contacts m^4 m^5 which are only held apart by the cam when the ring M^2 is out of action, so that immediately after the first pawling of M^2 solenoid o^4 is 50 excited and remains so when the parts are in a position for conversation. The arm o^9 makes an angle with the pawl o^2 , and when the armature o^3 and arm o^9 are moved inward toward the casing M by reason of excitation of the solenoids o^4 and o^5 , the pawl o^2 is pushed on to a smooth part of the ring M^2 , the magnet O being rotated at the same time. The weight P^1 tends now to turn back 55 arm M^1 in its initial position, but this movement is prevented, because simultaneously with the solenoid o^5 the magnet N is excited and its rod n^1 is pushed in the hole c^8 of the button c^6 (Figs. 1 and 20). When the circuit of battery I is broken and thereby the attracting force of magnet N upon its arm-

ture n is suspended, the rod n^1 is pushed out of the hole c^8 by the spring n^2 . Now arm M^1 can be turned back stationary by the weight P^1 . Although solenoid o^5 is shut out simultaneously with magnet N the former remains by influence of the solenoid o^4 against the effect of spring o^6 . Thereby the pawls o^2 and o^8 cannot enter the teeth of M^2 during the returning of arm M^1 .

When arm M^1 and also magnet N reaches its initial position cam m^3 pushes the spring m^4 from the contact m^5 (Fig. 7), breaks the circuit of battery III and renders solenoid o^4 not excited, so that the attraction between o^4 and o^5 is suspended and spring o^6 pushes 70 solenoid o^5 , and the pawls o^2 and o^8 outward in the toothed part of M^2 . Repeated closing and opening of the circuit containing the coil of the magnet O causes the armature o^1 to be repeatedly attracted and released again, and the ring M^2 is rotated, to the extent of one tooth, as often as the armature o^1 is attracted. The number of teeth of M^2 is such that magnet N by each full turn 75 of a drum V, hereinafter more particularly described is brought by magnet O from one pair of magnets A and B to the next one. Starting from its normal position magnet N stands therefore after six turns of drum V before the magnets A⁶ B⁶. The line wires which connect the magnets A¹...A¹⁰ have 80 respective ends connected to the contact disks c^1 , while the remaining ends are connected to the rods F¹...F²⁰. The return is for the upper magnets A from the contacts d^1 ... d^{10} through the coil of the magnet O to earth. The return is for the lower magnets A over the grounded ring E, which is touched by the levers G in the position of rest. Current from the local battery VII 85 flows continuously through the coils of the upper magnets B, and through the coils of the lower magnets B in different directions depending on the position of the plates b^5 and b^6 .

Fig. 9 shows the selecting-switch, which must be employed for each group of subscribers, and which is nearly equal to the selecting-switch shown in Fig. 1 serving to connect the several groups. The differences between the switches of Figs. 1 and 9 will now be described. The ring E² in Fig. 9 substituted for the ring D of Fig. 1, is of metal, and the holes e therein for the passage of the rods C¹...C¹⁰ lined with insulating material. The contact-plates d^1 ... d^{10} in Fig. 9 are fixed to the casing M and are so narrow that they do not remain in contact with the disks c^1 during the entire movement of the latter. When the said disks are in contact with the ring E, current flows through the latter. The upper rods C¹...C¹⁰ have disks q fixed to their outer ends, adapted to abut against and electrically connect rings q^1 and q^2 fixed to the wall of the casing M. 130

One of the disks g also serves as armature for a magnet Q which is placed on an extension of the rod C^1 slideable in the said magnet and serves to connect the selecting-switch of one group of subscribers with the selecting switch common to all groups. One terminal of the coil of the magnet Q is connected to the ring q^2 and the other to a terminal of a local battery II . The battery II is connected to the ring q^1 , so that the electro-magnet Q is in a shunt-circuit of the battery II . In their positions of rest the levers $G^1 \dots G^{10}$ belonging to the upper rods C are in contact with a disk e^1 fixed to the magnet-core E^1 of electro-magnet J^2 . The slide-contacts for reversing the current in the lower coils $B^1 \dots B^{10}$ work as those of Fig. 1 and the magnets B are connected in equal manner as in the switch of Fig. 1, only the size of their sliding-surfaces differs from that of Fig. 1 in such a manner that the lower magnet B is short circuited and receives no current when the lower magnet B is adjacent to magnet A but, the corresponding upper magnet B is repulsed from A . (Fig. 9).

As shown in Figs. 19 and 21 the line circuit passes from the terminals $K^1 \dots K^{10}$ over the sliding rods $h^1 \dots h^{10}$ and the rods $F^1 \dots F^{10}$ through each magnet-coil A to upper and lower rods $C^1 \dots C^{10}$. Now the route of the current differs from that of Fig. 1 as it passes through the lower electromagnets A , over the contacts $d^1 \dots d^{10}$ and through the magnet O of the driving pawl to the ground, while the upper magnets A are connected with the ground over the levers $G^1 \dots G^{10}$ which touch in their position of rest the grounded annular contact E^1 . Current from the local battery II flows (as in the switch of Fig. 1) through the coils o^5, J^2 and N . The battery II also feeds, as aforesaid, the electro-magnet Q , to which it is connected by separate wires. Another battery IV supplies current to the solenoid o^4 , as at the switch of Fig. 1. If, as aforesaid, in the case of a small number of subscribers, only one single selecting-switch has to be used, it is only necessary to change the apparatus shown in Fig. 9 in such a manner, that magnet Q is omitted, as its function of connecting the selecting-switch of one group with the selecting-switch common to all groups is unnecessary. The upper electro-magnets A B may also be omitted, because, as hereinafter described, only the lower magnets A B are needed. The contacts b^2, b^3, b^4 are not movable.

A switch-board (Fig. 11) has a series of contact-plates $r^1, r^2, r^3 \dots$ and a hand-lever R . In a box fixed to the board there is a cylinder V of non-conductive material, which is fixed to a spindle V^1 and carries a metal ring v with teeth $v^1 \dots v^{10}$. A brush t^5 is in continuous contact with the ring,

and a brush t^4 is so placed that during rotation of the ring it is alternately in contact with teeth $v^1 \dots v^{10}$ and with the non-conductive cylinder V . The brushes t^4 and t^5 are connected to the line. Behind the cylinder V there is a key S of non-conductive material, normally thrust upward by a spring s^1 . To the shank s^2 of this key two contact-plates s^3 and s^4 (Fig. 13) are symmetrically fixed, which are connected with the line wire battery V (Fig. 15), and are normally in contact with contacts t and t^3 under the influence of spring s^1 . If the key S is struck the contact-plates s^3 and s^4 are momentarily thrust against contacts t^1 and t^2 below them. The contacts t, t^1, t^2, t^3 are as is evident from Figs. 15 and 17 connected with each other and with the line wire in such a manner that the current flowing to the contact-plates s^3 and s^4 is for a moment reversed in the line wire if the key S is struck.

To indicate whether the key S has been sufficiently depressed to reverse the current, two pairs of fixed solenoids x^1, x^2 and springs y^1 (Fig. 14) are provided for the connections of the same group selecting switch and for the connecting to other selecting-switches. The cores of these solenoids move in accordance with the direction of current, and cause differently colored disks to alternately appear behind windows y ; for example, white:—No call; blue: Short distance call; red: Long distance call. The manner in which the solenoids x^1 and x^2 co-act with the springs y^1 is similarly to that already described in connection with the devices A B c and $o^4 o^5 o^6$, one of the solenoids being fixed and the other movable with the core, which is thrust in one direction by the spring. The movable solenoids are connected to battery VII , and the fixed solenoids to the line-circuit of the battery V .

Each of the telephones W is connected to ground and to the contact-plate r^1 . The contact-plate r^2 is connected to the terminal h of the lower magnets A , and the contact-plate r^3 is connected to the terminal h of the upper magnets A . The contact-plate r^4 is joined with the hook of the receiving instrument and with the earth. Lever R stands normally between the contact-plates r^1 and r^2 joining them both.

In the case of only a small number of subscribers, wherein only one single selecting-switch is provided, the connection between two subscribers is reached in the manner shown in Figs. 15, 16 and 17. The selecting-switch then used is that shown in Fig. 9, only magnet Q , the upper magnets A, B , rods C , parts G^1, L, F^1 and ring E^2 being omitted, the contact b being fastened to the cover of the casing M .

Let it be assumed, for example, the telephone No. 1 (Fig. 15) is to be connected,

through the selecting-switch (Fig. 16), to telephone No. 6 (Fig. 17). For this purpose the calling subscriber No. 1 places his lever R on contact plate r^2 . The calling subscriber 5 then rotates his cylinder. The current flowing through the circuit thus closed causes the arm M¹ to be rotated by the electro-magnet O, in order to place the magnet N in front of the magnets A⁶ B⁶. The circuit is as follows:—from earth 5 (Fig. 15) to contact-plate r^4 , contact t of the key S, battery V, brush t^5 , cylinder V, one of the teeth u , brush t^4 , contact s^4 , contact t^5 , lever R, contact-plate r^2 , line 1, terminal K¹ (Fig. 16), 10 plate h^1 , rod F¹, lower magnet A¹, disk c^1 , contact d^1 , branch wire 3, magnet O, to earth at 4. During the rotation of the cylinder V intermittent current impulses are, therefore, sent through the coil of the electro-magnet 15 O. Each current impulse causes the armature o^1 to be attracted and the ring M² to be rotated to the extent of one tooth. The upper magnets B which constantly receive current from the local battery VII (Fig. 16) 20 adhere to their magnets A by magnetic influence, as the force of the springs c is less than the magnetic attraction. The magnets B adhere to their magnets A during the current impulses sent through the latter because for one reason the strength of the current sent through the magnet B¹ from the local battery VII is such that induction or 25 residual magnetism causes the magnet B¹ to resist the thrust of the spring c , but when 30 magnet A¹ has no current, and because for the other reason the direction of the current of the line wire effecting the turning of M¹ is such that it produces in that end of the magnet A¹ to which adheres magnet B¹ a 35 polarity dissimilar to that produced in the adjacent part of magnet B¹ by the local current of battery VII. Therefore to move the magnet B¹ radially inward there must be 40 sent through magnet A¹ a current whose direction is opposite to that, which serves to turn arm M¹. This reversal of the current in the line wire is produced by a stroke upon the key S. When the magnet B¹ is moved 45 radially inward the contacts b^5 and b^6 , previously under b^3 and b^4 , are placed under the contacts b^2 and b^3 . Thereby in the coil of the magnet B¹ the direction of the current 50 is reversed, and consequently the polarity of the magnet is changed. But at the same time 55 cessation of the depression of the key S which has to be done very quickly causes flow of the current in the original direction and thereby the original polarity of the magnet A is restored, so that the adjacent 60 ends of the magnets A and B then have again like polarity. If the polarity of the removed magnet B¹ were not changed the said magnet would be attracted again by the magnet A¹ when the depression of 65 the key ceases. The rod C¹ moves inward,

with the magnet B and disk c^1 fixed thereto. The contact between the said disk and d^1 is broken, and the circuit energizing the magnet O is thus opened, while the magnet A¹ is connected with the ring E, as the disk c^1 touches the ring E by repulsion of magnet B¹. The coils of all the other magnets A remain connected through the disks c^1 and contacts d^1 to the wire leading to the magnet O, and all the other magnets B remain adhering to the magnets A. Only the magnet B¹ is moved. By this means the disk c^6 on the rod C¹ is brought into contact with the contact rings c^6 and c^7 and thus closed, in conjunction with the brush n^3 , the circuit containing the battery I. This circuit (Fig. 17) goes over contact-ring c^7 , disk c^3 , contact ring c^6 , brush n^3 , magnet N, magnet J², magnet o⁵, back to battery I. The magnet N attracts its armature n and moves the rod n^1 85 into engagement with the recess c^8 in the knob c^5 in line with it. The attraction of the armature n causes the corresponding lower rod C⁶ to move inward, and the disk c^1 on the said rod is thrust against the ring E. 90 The two telephones are thus connected to each other, since the energizing of the magnet J² and N causes the cylinder H to be attracted and the contact between the other rods F and plates h to be broken, while the 95 rods F¹ and F⁶ of which F¹ has been moved already downward, when magnet B is repulsed and F⁶ by excitation of magnet N, now follow the downwardly moved plates h and remain in contact therewith. In this condition the selecting switch station is disconnected from all the telephones with the exception of No. 1 and No. 6. At the same time with magnet N the magnet o⁵ included 100 in the circuit of the local battery I also is excited and attracted by the fixed magnet n^4 which has received current by the local battery III. Thereby the armature o^3 , the pivoted holding pawl o^8 and the driving pawl o^2 are moved radially inward by the forked rod o^6 which turns the magnet O and releases the teeth M². The weight P¹ tends now indeed to turn back arm M¹ in its initial position, but that is prevented, as aforesaid, as the excited magnet N has attracted his armature n and the core n^1 has entered the hole c^8 of the head c^5 . 110

The connection between the exchange switches of telephones No. 1 and No. 6 (Figs. 15 and 17) is as follows:—from ground 5 in the already described manner over battery V to the line wire l , thence to plate h^1 , rod F¹, magnet A¹, disk c^1 of the rod C¹, ring E, disk c^1 of the rod C⁶, magnet A⁶, rod F⁶, plate h^6 , line wire 6 to terminal r^2 , and 115 through the exchange switch of telephone No. 6 over the lever R touching in its position of rest the contact plates r^2 and r^1 , to r^1 and from there over the coil of the bell-magnet and the hook of receiver to the earth. 120 125 130

The called subscriber, whose attention is excited by the bell, takes off his receiver, breaks thereby the circuit of the receiver contact plate to the bell and sets the latter in rest. Meanwhile on the calling telephone lever R is placed between r^1 and r^2 . The two telephones are then ready for conversation to take place, while drum V is separated from R. As aforesaid, the proper telephones are connected with the terminal r^1 and the earth. Now the calling subscriber takes off his receiver and the conversation-current flows:—ground at 5, telephone No. 1, one coil of inductor W³ contact-plate r^1 , 10 over the lever R to contact-plate r^2 , line wire l, terminal K¹, (Fig. 16) plate h¹, rod F¹ to the lower magnet A¹ and the corresponding disk c⁶ on the core C¹, ring E, disk c¹ through the magnet A⁶, the rod F⁶, plate 15 h⁶, over the line wire 6 to the contact plate r^2 of telephone No. 6, over the lever R, contact-plate r^1 , coil of inductor W³ to the telephone of the called subscriber No. 6 to the earth and through the latter back to telephone No. 20 1. The microphone W¹ and the other coil of inductor W³ lie in the circuit of the battery VI which is closed when the receiver is removed from its hook. If the conversation is finished, the lever R of the calling 25 telephone No. 1 is moved back to contact-plate r^2 , and the key S is temporarily depressed. This causes current to flow through the magnets A¹ and A⁶, and the magnets B¹ and B⁶ are attracted by the magnets A while 30 the key is depressed. At the same time the circuit of the magnet N is opened owing to the removal of the disks c³ on rods C¹ and C⁶ from the rings c⁶ and c⁷, and B⁶ can follow the attraction of A⁶. The lower contact 35 plates b⁵ and b⁶ are again placed under the plates b³ and b⁴, and the polarity of the magnets B¹ and B⁶ is changed. The key is at the same time released, and a current is again sent through the magnets A. The adjacent ends of the magnets A and B being 40 now of opposite polarity the magnets remain in contact with each other until the key is again quickly depressed. As the breaking of the current in magnet N renders also the magnets J² and o⁵ currentless, the slider H by the power of spring J¹ returns in its initial position, and the weight P¹ can turn back arm M¹ in the initial position. The lever R of the calling telephone 45 50 55 No. 1 is placed between the contact-plates r^1 and r^2 , and the subscriber who had given the call can be called up by any of the other subscribers.

For making and breaking the connection 60 between two telephones through one single selecting-switch for purposes of conversation, the following operations are, therefore, required at the calling subscriber's apparatus:—(1) Adjustment of lever R on the 65 contact plate r^2 of the wire leading to the

lower magnet A. (2) Rotation of cylinder V. (3) Short depression of the key S. (4) Adjustment of lever R between contacts r^1 and r^2 . (5) Return of lever R to r^2 . (6) Short depression of the key S. (7) Adjustment of lever R between the plates r^1 and r^2 . 70

Figs. 18 to 22 illustrate the connection between two telephones in the case of different groups of for instance 10 subscribers in each 75 group. Let it be assumed, that for instance the subscriber No. 2 of group No. I (Fig. 22) will be connected with the subscriber No. 7 of group III (Fig. 18). For this purpose the calling subscriber No. I—2 connects 80 at first the selecting switch (Fig. 21) belonging to his group, with the selecting switch (Fig. 20) common to all groups, joins now this latter selecting-switch with that one belonging to the group of the subscriber to be 85 called (Fig. 19) and fits it finally on the line wire contacts of the telephone No. III—7 to be called (Fig. 18).

For making the connection between the telephones I—2 and III—7 there has to be 90 done in detail the following:—

(1) Lever R (Fig. 22) is adjusted over contact plate r^3 . The line current excites the coil A² of the upper magnet pair (Fig. 21) and goes back to the earth, on the following path: earth at 1—2 (Fig. 22), contacts r^4 , t, s³, battery V, brushes t⁴, t⁵, contacts s⁴, t³, lever R, contact r^3 , line wire 2, sliding rod h² (Fig. 21), rod F², upper magnet A², disk c¹, upper contact E², lever G², 95 cylinder E¹ to earth. By the excitation of A² the magnet B² is repulsed and draws with it the disk q. Thereby, in the same manner as magnet N in the example given hereinbefore, magnet Q is inserted and 100 thereby the selecting switch (Fig. 21) is connected with the one (Fig. 20) common to all groups. The current of magnet Q flows from battery II over ring q⁴, disk q, ring q² to coil Q and from there back to battery 105 II. The connection with the central selecting switch (Fig. 20) takes place through the following circuit: from the earth at I—2 (Fig. 22) in the manner hereinbefore described to the upper magnet A², to the corresponding disk c¹, adhering at ring E² by repulsion of B², ring E² to the disk c¹ of the core C¹ of magnet Q, through the magnet A⁶ of this core, rod F⁶, sliding rod h⁶ over line 110 wire 1 to sliding rod h¹ of the selecting-switch (Fig. 20), rod F¹, magnet O to earth. By excitation of the upper magnets A⁶ and A² (Fig. 21) the adhering magnets B⁶ and B² are repulsed, the contact between b⁴ and b⁶ is broken and the lower magnets B⁶ and B² receive no current. Therefore they will 115 be repulsed from their magnets A⁶ and A² by the spring c. By this repulsion contact is made between c⁶ c³ c⁷, magnet J² is excited and the cylinder H moves downward, 120 125 130

where the rods F^2 and F^6 are already pushed so that the conversation circuit of the lower magnets A is completed. On the central selecting switch (Fig. 20) the upper magnet B^1 is repulsed also from its magnet A by excitation but the lower magnet B^1 will not be repulsed thereby, because it still receives current as the sliding contacts are suitably arranged for this purpose.

10 (2) The drum V of the calling telephone is turned three times. The current impulses sent thereby to the central selecting switch (Fig. 20) in the described manner move arm M^1 opposite the core rod c^3 .

15 (3) On the calling telephone No. I (Fig. 22) the lever R is adjusted over the plate r^2 and the key S is then momentarily depressed. There is thereby sent a current of opposite direction to the lower magnets A of the selecting switches (Figs. 21 and 20) through the following circuit:—from the ground at I—2 (Fig. 22) to contact r^4 , over the path as hereinbefore described, through this subscriber's apparatus to contact r^2 and 25 the line wire 2', to h^2 , F^2 (Fig. 21), lower magnet A^2 , disk c^1 , ring E, to disk c^1 of lower magnet A^0 , A^0 , F^0 , h^0 , line wire I' to the central selecting switch (Fig. 20), there over h^1 , F^1 to the lower magnet A^1 , disk c^1 , core C^1 , cylinder E^1 to earth. By 30 this current the armature of the lower magnet B (Fig. 20) is repulsed and disconnected from the local battery VII. At the same time by the contact c^3 , c^6 , c^7 the electro- 35 magnets N, J^2 and o^5 are connected to the local battery II of the central selecting switch (Fig. 20). Thereby the following circuit to the selecting switch (Fig. 19) of the group of the subscriber No. III—7 to be 40 called is completed:—by the circuit already described from telephone No. I—2 (Fig. 22) over the lower magnets A^2 and A^0 (Fig. 21), to the lower magnet A, (Fig. 20), winding E of the lower magnet A_m , F^0_m , h^0_m , 45 line wire for station III', h^0_m , F^0_m (Fig. 19), lower magnet A^0_m , disk c^1 , contact d , magnet O to earth.

46 (4) Drum V of the calling subscriber is turned seven times and the key S is depressed. Now the telephones in question are connected. By turning the drum V 7 times the arm M^1 is actuated by the current impulses passing through the magnet O and brings the magnet N to its operative position relative to the contacts and the magnets A B^7 of the called subscriber. By depression of key S and the current impulse of opposite direction produced thereby the lower magnet B^0_m (Fig. 19) is repulsed, contact c^3 c^6 50 c^7 is closed, magnet N excited and magnet B^7 also repulsed. Now from telephone No. I—2 to telephone No. III—7 the following circuit is completed:—earth at I—2 (Fig. 22), contacts r^4 , t , s^3 , battery V, contacts t^4 , t^5 , s^4 , 55 t^8 , lever R, contact r^2 , line wire 2', to the se-

lecting switch (Fig. 21), h^2 , F^2 , lower magnet A^2 , ring E, lower magnet A^0 , F^0 , h^0 , line wire I' , central selecting switch (Fig. 20), h^1 , F^1 , lower magnet A^1 , ring E, lower magnet A_m , F^0_m , h^0_m , line wire for station III' to selecting switch (Fig. 19), h^0_m , F^0_m , lower magnet A^0_m , ring c , lower magnet A^7 , F^7 , h^7 , line wire 7, to telephone No. III—7, contacts r^2 , r^4 , bell, hook of receiver to ground. 70

75 (5) After finishing the conversation the lever R of the calling telephone is moved to contact-plate r^3 , and the key S is then depressed. In all three selecting switches the upper magnets B move back to the respective magnets A.

80 (6) Lever R is moved to contact-plate r^2 and the key S is then depressed. In all three selecting switches the lower magnets B move back to the respective magnets A.

85 (7) At last the calling subscriber moves his lever R between contacts r^1 and r^2 and thereby the position of rest is restored.

90 What I claim as my invention and desire to secure by Letters Patent of the United States is:—

1. In an automatic telephone system, the combination of a plurality of telephones, a line circuit for each telephone, a selecting switch apparatus, comprising a talking contact and a series of rods, means operated by 95 said line circuit for moving the rod corresponding to the calling telephone to, and off said talking contact, a local circuit, means for closing said local circuit, a motor operated by said line circuit, an arm moved by 100 said motor, an electro-magnet carried by said arm and brought to the rod corresponding to the telephone of the called subscriber, said electro-magnet being excited by said local circuit for moving the last named rod 105 to said talking contact and means for returning the parts to their initial position.

2. In an automatic telephone system the combination of a plurality of telephones, a line circuit for each telephone, a selecting 110 switch apparatus comprising a central placed talking contact and a series of rods arranged radially to the said contact, means operated by said line circuit for moving the rod corresponding to the caller's telephone 115 to said contact, a local circuit closed by the moved rod, a motor comprising an electro-magnet excited by said line circuit, an arm moved by said motor circularly about the selecting switch apparatus, an electro-magnet 120 carried by said arm and brought to the rod corresponding to the telephone of the called subscriber, said electro-magnet being excited by said local circuit for moving said rod to said talking contact, and means for 125 returning the parts in their initial position.

3. In an automatic telephone system the combination of a plurality of telephones, a line circuit for each telephone, a selecting switch apparatus comprising a talking con- 130

- tact and a series of rods, means operated by said line circuit for moving the rod corresponding to the caller's telephone to said contact, a pair of electro-magnets on each of 5 said rods, for operating said means and for removing said rod, one of said electro-magnets being stationary and inclosed in said line circuit while the other is movable with the rod, a local circuit in which the moved 10 electro-magnet is included, connections for reversing the polarity of the movable magnet, another local circuit closed by the moved rod, a motor operated by said line circuit, an arm moved by said motor, an electro-magnet carried by said arm and adapted to 15 be brought to the rod corresponding to the telephone of the called subscriber, said electro-magnet being excited by said other local-circuit for moving said rod to said talking contact, and means to return said arm in its initial position on breaking of said other local circuit by removing the rod corresponding to the caller's telephone by the 20 operation of the line circuit.
- 25 4. In an automatic telephone system the combination of a plurality of telephones, a line circuit for each telephone, a selecting switch apparatus, comprising a talking contact and a series of rods, means for moving 30 the rod corresponding to the caller's telephone to said contact, a fixed magnet surrounding each rod and included in said line circuit, a magnet movably disposed on each rod, a local circuit in which the moved electro-magnet is included, means for reversing 35 the current in said fixed electro-magnet to produce repulsion of said movable electro-magnet and to restore the polarity of said fixed electro-magnet, connections between 40 said local circuit and said movable electro-magnet for reversing its polarity, a second local circuit, closed by the moved rod, a motor operated by said line circuit, an arm moved by said motor, an electro-magnet carried by 45 said arm and adapted to be brought to the rod corresponding to the telephone of the called subscriber, said electro-magnet being excited by said second local-circuit for moving said rod to said talking 50 contact, and means to return said arm in its initial position on breaking of said other local circuit by removing the rod corresponding to the caller's telephone by the operation of the line circuit.
- 55 5. In an automatic telephone system the combination of a plurality of telephones, a line circuit for each telephone, a selecting switch apparatus comprising a talking contact and a series of rods, two electro-magnets on each rod for controlling its 60 movement, one of said magnets being fixed on the rod whereon it is mounted and the other slidable on said rod, a spring for moving the rod corresponding to the caller's 65 telephone to said contact, the strength of

the spring being less than the force of attraction due to excitation of both electro-magnets when the latter are apart, and less than the force of attraction due to excitation of the one electro-magnet alone when it 70 is in contact with the other magnet, but greater than the force of attraction due to excitation of one of the magnets when the latter are apart.

6. In an automatic telephone system the combination of a plurality of telephones, a line circuit for each telephone, a selecting switch apparatus, comprising a talking contact and a series of rods, means operated by said line circuit for moving the rod corresponding to the caller's telephone to said contact, means for restoring said rod to its initial position, a local circuit closed by the moved rod, means operated by said local circuit for moving the rod corresponding to the 80 telephone of the called subscriber to said talking contact, an electro-magnet included in said local circuit, a second contact connected in its position of rest with all of said rods and operated by said electro-magnet to 85 break the connections with the remaining rods when two of said rods are moved.

7. In an automatic telephone system the combination of a plurality of telephones, a line circuit for each telephone, a selecting switch apparatus comprising a talking-contact and a series of rods, means operated by said line circuit for moving the rod of the caller's telephone to and from said contact, a local circuit closed by the moved rod, a 95 motor comprising an electro-magnet operated by said line circuit, an arm moved by said motor, an electro-magnet included in said local circuit carried by said arm and adapted to be brought to the rod of the 100 called telephone for moving this rod to said talking contact, means for returning said arm to its initial position on breaking of the 105 said local circuit by removing the rod corresponding to the caller's telephone, a 110 pawl releasably preventing the removing of said arm, and an electro-magnet included in said local circuit to release said pawl when energized.

8. In an automatic telephone system, the combination of a plurality of telephones, a line circuit for each telephone, a selecting switch apparatus comprising a talking-contact and a series of rods, means operated by said line circuit for moving the rod of the 115 caller's telephone to and from said contact, a local circuit closed by the moved rod, a motor comprising an electro-magnet operated by said line circuit, an arm moved by 120 said motor, an electro-magnet included in said local circuit and carried by said arm and adapted to be brought to the rod of the called telephone for moving this rod to said talking contact, means for returning said arm to its initial position on breaking of the 125 130

- said local circuit by removing the rod corresponding to the caller's telephone, a toothed ring on said arm, a pawl connected with said motor and engaging said toothed ring
- 5 for moving said arm in one direction and holding the arm when moved, a movable electro-magnet connected to said pawl and included in a proper local circuit, a fixed electro-magnet in the local circuit, closed by
- 10 the caller's rod, said movable electro-magnet being arranged to release said pawl from the toothed ring, and contacts in the first mentioned local circuit adapted to be broken by return of the arm.
- 15 9. In an automatic telephone system the combination of a plurality of telephones forming groups, a selecting switch apparatus, serving as subcentral station to each group and connected by a line circuit with
- 20 each telephone of its group, a selecting switch apparatus serving as central station to all selecting switch subcentral stations and connected with each of them, a line circuit, each selecting switch apparatus being
- 25 provided with a pair of contacts, two series of rods, a fixed and a movable magnet on each rod, means for moving the two rods corresponding to the caller's telephone and to that of the subscriber to be called to thereby
- 30 close said contacts, and means for returning all of the parts to their initial positions.
10. In an automatic telephone system, the combination of a plurality of telephones forming groups, a selecting switch apparatus
- 35 serving as subcentral station to each group and connected by a line circuit with each telephone of its group, a selecting switch apparatus serving as central station to all selecting switch subcentral stations and connected with each of them by a line circuit, each selecting switch apparatus including a pair of contacts, two series of rods, there being a pair of rods for each telephone, means for operating said rods, means for returning all parts to their initial positions,
- each rod being provided with one fixed and one movable electro-magnet, the two fixed electromagnets of each pair of rods being included in the line circuit of the corresponding telephone, one of the two movable 50 electro-magnets of each pair being included in a local circuit and both movable electromagnets being provided on their adjacent parts with contacts which change their relative position when said electromagnets are 55 displaced with their rods, said contacts being arranged to close the local circuit through the remaining movable magnet, said circuit being closed at a predetermined point in the movement of the first movable magnet and 60 open at all other points.
11. In an automatic telephone system the combination of a plurality of telephones, a selecting switch apparatus serving as sub-central station to each group, a receiving 65 switch apparatus serving as central station to all selecting switch subcentral stations, each selecting switch apparatus including two contacts, two series of rods, means for operating said rods, and means for returning 70 all parts to their initial position, a local circuit having contacts, the one series of rods of the selecting switch subcentral stations being provided with means for closing the circuit through an electromagnet excited by 75 said local circuit and thereby operating the central selecting switch station, to make the connection with the selecting subcentral station of the group to which belongs the telephone of the subscriber to be called and to 80 operate thereby this subcentral station to make the connection with the called telephone.
- In testimony that I claim the foregoing as my invention I have signed my name in 85 presence of two subscribing witnesses.
- VALERIAN ALEXEEFF.
